UNITED STATES PATENT OFFICE.

HERBERT H. HEWITT, OF BUFFALO, NEW YORK.

CAR-TRUCK.

1,123,293.

Specification of Letters Patent.

Patented Jan. 5, 1915.

Application filed May 8, 1912. Serial No. 696,026.

To all whom it may concern:

Be it known that I, HERBERT H. HEWITT, a citizen of the United States, and a resident of Buffalo, county of Erie, and State of New York, have invented certain new and useful 5 Improvements in Car-Trucks, of which the following is a full, clear, and exact description.

The invention relates to car trucks of the 10 type set forth in Letters Patent of the United States No. 1,009,747, issued to me November 28, 1911, and in which the side frames of the truck have an independent rocking movement relatively to the transverse connecting 15 means between them, so that the four wheels of the truck may all rest solidly on the track in spite of irregularities therein.

The present invention seeks to improve the 20 construction of the side frame and manner of mounting the journal boxes thereon and consists in the features of improvement hereinafter set forth, illustrated in the accompanying drawings and more particularly pointed out in the appended claims.

25 In the drawings, Figure 1 is a plan view of one-half of the truck with portions of one of the side frames and the journal box shown in horizontal section. Fig. 2 is a side elevation with half of the side frame and the 30 journal box shown in vertical section. Fig. 3 is a detail section on the line 3 of Fig. 2.

Each of the side frames of the improved 35 truck is formed of a single, integral body of metal and is substantially diamond-shaped in outline. The side frame comprises an enlarged central portion 10 and side arms 11 which extend from the upper and lower parts of the central portion 10 and which converge and are connected at the ends of the side 40 frame. The pairs of side arms 11 form in effect upper and lower arch bars. The central portion 10 and the arms 11 are formed of a central, integral web having a wide marginal flange 12 at their outer edges. The 45 outer ends of the arms 11 are preferably connected by web portions 13 and the inner edges of the arms and of the portions 13 are provided with narrow, marginal strengthening flanges 14.

50 The car truck is provided with the usual wheel axles 15 having wheels 16 thereon and projecting end journals 17. The journals 17 extend within journal boxes 18 which are of usual shape, but which are formed integral with the side frames. The upper and lower 55 marginal flanges 12 of the side frames and

the web 13 merge, as shown, into the inner side walls 19 of the journal boxes and the latter are formed integral with the top and bottom walls 20 and 21 of the boxes and with 60 the outer side walls 22. The top and bottom marginal flanges 12 of the side frames preferably taper slightly from the central portion of the side frame toward the ends thereof, but at the ends of the side arms, the 65 outer marginal flanges 12 are provided with outwardly curved portions 23 which merge into the walls of the journal boxes. Strengthening flanges 24 extend centrally over the upper portions of the upper side 70 arms 11 and over the top wall 20 of the journal boxes. Smaller strengthening flanges 25 extend between the ends of the lower side arms 11 and the bottom walls of the journal boxes. These flanges are, of course, formed 75 integral with the parts connected and strengthened thereby. The journal boxes are provided with integral wedge guides 26 and with lids 27 of any suitable form. Each box is also provided with the usual 80 journal bearing *a* and wedge or key *b*.

The enlarged central portion 10 of the side frame is provided with a transverse circular opening having a marginal flange which projects on opposite sides of the central web of the side frame and forms a transverse cylindrical bearing 28. The cylindrical bearing flanges 28 are preferably somewhat wider than the outer marginal flanges 12 and integral, inclined strengthening ribs 85 29 extend between these flanges. The transverse connecting means between the side frames is provided with cylindrical end members 30 which are journaled within the enlarged central bearings 28 of the side 90 frames to permit the rocking movement of the latter. The side frames are detachably held in position by keys 31 which fit within pockets 32 formed in the frame at opposite sides of the central bearing portion 28 and 95 removably held in position in the pockets by bolts 33. The keys project inwardly through elongated slots 34 formed in the cylindrical member 30. In this way the side frames are 100 detachably interlocked with the cylindrical 105 bearing members, but are free to rock to a limited extent relatively thereto and relatively to the transverse connecting means between the side frames.

In the construction shown, the cylindrical 110 members 30 are, in effect, trunnions formed upon the ends of the truck transom. The

transom shown comprises side portions 35 which are connected at their ends and provided with the cylindrical members or trunnions 30. A bolster 36 arranged between the 5 sides of the transom is supported at its ends in the usual manner by springs 37.

In the improved construction, each side frame comprises the enlarged cylindrical bearing portion 28, the arms 11 and the journal boxes 18, all formed of a single integral body of metal and preferably of a steel casting. This construction provides a side frame of great strength and rigidity, but at the same time the side frames are flexibly 10 connected and are free to rock independently of one another and relatively to the transverse connecting means between them, so that the wheels of the truck will follow irregularities of the track without straining 15 or distorting the parts of the truck.

It is obvious that changes may be made in the details set forth without the departure from the essentials of the invention as defined in the claims.

25 I claim as my invention:—

1. A car truck comprising side frames, each consisting of an enlarged central portion having a transverse, flanged, cylindrical bearing opening, integral upper side 30 frames extending outwardly and downwardly from the upper portions of said cylindrical bearing and lower side arms extending outwardly and upwardly from the lower portions of said bearing, and integral journal boxes connecting the converging 35 ends of said upper and lower side arms, the axes of said journal boxes being in substantial horizontal alignment with the axis of

said cylindrical bearing, and transverse connecting means between said side frames having cylindrical end members journaled in the central bearings thereof to permit the rocking movement of said side frames, substantially as described. 40

2. A side frame for car trucks comprising 45 an enlarged central portion having a transverse, cylindrical, flanged bearing opening, integral converging side arms extending from the upper and lower portions of said enlarged central portion and connected at 50 their ends and integral journal boxes at the ends of said side arms, said enlarged central portion and said arms comprising a central web and inner and outer edge flanges, said outer edge flanges merging into the 55 walls of said journal boxes and vertical, longitudinally extending central flanges extending between said arms and the upper and lower walls of said journal boxes, substantially as described. 60

3. A side frame for car trucks comprising 65 an enlarged central portion, having a transverse, cylindrical bearing, converging side arms extending from the upper and lower portions of said bearing and journal 70 boxes at the ends of said side arms all formed integral with a single body of metal, the axes of said journal boxes being in substantial horizontal alignment with the axis of said cylindrical bearing, substantially as described. 75
